UNITED STATES PATENT OFFICE.

GEORGE W. MORTHLAND, OF LEAD, SOUTH DAKOTA.

ORE-GRINDING MACHINE.

1,363,990.

Specification of Letters Patent. Patented Dec. 28, 1920.

Application filed December 20, 1918. Serial No. 267,636.

To all whom it may concern:

Be it known that I, GEORGE W. MORTHLAND, a citizen of the United States, residing at Lead, in the county of Lawrence and State of South Dakota, have invented new and useful Improvements in Ore-Grinding Machines, of which the following is a specification.

This invention relates to crushing and grinding machines, particularly to that type employed for crushing and grinding ores, and has for its object the provision of a grinding machine of the tube mill type which includes a rotating tapered casing within which is disposed co-acting disks of different diameters and provided upon their confronting faces with recesses engaging and crushing the material fed axially through the device, all of the disks rotating at different speeds whereby they will move relatively to one another whereby to obtain the maximum grinding effect upon the material, the disks furthermore rolling upon the material disposed between their peripheries and the inner periphery of the tapered casing.

An important object is the provision of a tube mill of this character in which the disks progressively decrease in thickness whereby the number of grinding surfaces will be increased toward the discharge end of the device whereby coarse material fed into the device may in one operation be reduced to extreme fineness.

Another object is the provision of a device of this character which may be used with either a current of air or a current of water as the means for progressing the material through the device from the inlet to the outlet end thereof.

Still another object is the provision of a device of this character in which the rotating disks are formed of sections, the outer section being removable and replaceable in case of wear.

Another object is the provision of a device of this character which will be comparatively simple and inexpensive in manufacture, highly efficient in use, durable in service, efficient in operation and a general improvement in the art.

With the above and other objects and advantages in view, the invention consists in the details of construction to be hereinafter more fully described and claimed, and illus-

trated in the accompanying drawings, in which:

Figure 1 is a longitudinal sectional view through my device complete.

Fig. 2 is a cross sectional view through the same showing one form of disks,

Fig. 3 is an elevation illustrating a modified form of disks,

Fig. 4 is a cross sectional view on the line 4-4 of Fig. 3,

Fig. 5 is an elevation illustrating a still further modified form of disks, and

Fig. 6 is a cross sectional view therethrough on the line 6-6 of Fig. 5.

Referring more particularly to the drawings the numeral 10 designates the head at the inlet end of the device, this head having extending from its center a trunnion 11 provided with a central opening 12 forming an inlet opening. Bolted upon the other side of the head 10 is a flange member 13 to which is secured the larger end of a tapered casing 14 which is closed at its other end by a head 15 having extending from the center thereof a trunnion 16 provided with an opening 17 constituting the discharge opening of the device. A flange member 18 is bolted upon the head 15 and upon the tapered casing 14 for holding these parts securely assembled. The trunnions 11 and 16 are mounted in suitable bearings 19 so that the entire device may be rotated.

Disposed against the inner periphery of the tapered shell or casing 14 is a lining 20, preferably of wood, which is in turn engaged by a metallic lining 21 forming the inner shell. Bolted upon the heads 10 and 15 are hardened steel lining plates 22 and 23 respectively which have their peripheries engaging the inner periphery of the inner metallic shell 21. The purpose of the wooden lining 20 is to serve as a shock absorber for taking up a great deal of the shock incident to the use of the device.

Secured upon the larger end of the casing 14 and bolted to the flange member 13 and head 10 is a ring gear 24 which may be engaged by any suitable driven pinion for rotating the casing. It will be noted that the inner metallic casing 21, above referred to, is formed of longitudinally extending sections which are prevented from dislocation by the means of the lining plates 22 and 23 at the end of the outer casing.

Disposed within the interior of the inner

casing 21 is a plurality of disks 25, the alternate ones of which are of different diameters as clearly shown in Fig. 1. In the form of disks shown in Figs. 1 and 2 each 5 disk is shown as comprising a ring-like member having its outer periphery planed for rolling action in relation to the inner shell 21. Furthermore, each disk 25 has its faces provided with radially extending 10 grooves 26 which are V-shaped in cross section, as shown. It will be noted that the disks 25 at the larger end of the casing are of appreciably greater thickness than the disks at the smaller end of the casing and 15 that the disks progressively decrease in thickness toward the discharge end of the device.

The operation of the device is as follows: The casing is rotated in any desired manner 20 and the material to be crushed and ground is introduced through the opening 12 in the trunnion 11 and will pass into the openings in the centers of the grinding disks. In view of the fact that the disks 25 are of different diameters, these disks will be rotated at different speeds and will consequently rotate in respect to one another. The material falling into the openings within the disks will pass into the V-shaped 30 grooves 26 and will be crushed therein by the relative rotation of the successive disks. A portion of the material will pass through the radial grooves 26 to the outer periphery of the disks and will always be disposed at 35 the lower portion of the casing, the disks rolling upon this material and crushing it continually. If any of the material adheres to the inner lining 21, as the casing is rotated and this adhering material approaches 40 the top of the casing it will fall by gravity back onto the disks and be crushed further. In view of the fact that the casing is tapered there will be a tendency to cause the disks to gravitate toward the larger end of 45 the casing, thereby keeping the crushing disks in close contact with one another. The friction generated between the relatively rotating disks will prevent excessive shock against the sides of the casing. Owing to 50 the taper of the casing all of the disks, regardless of diameter, will travel a variable number of rim feet per minute, the smaller disks of course turning a greater number of revolutions than the larger ones, thereby 55 causing a continuous eccentric grinding motion between the planes of the disks as they roll forward in the line of travel. It will be noted that in view of the fact that the disks toward the discharge end of the 60 device are of less thickness than the disks toward the inlet end of the device that a greater number of grinding planes will be provided toward the discharge end and that the material will be consequently ground

more and more as the material is reduced to 65 smaller pieces.

It is understood, of course, that in the use of the device either a current of air or a stream of water must be employed for conducting the material into, through and 70 out of the device. After the device is in operation for some time and the material is reduced to the proper fineness, the out-flowing stream either of air or water will pass from the opening 17 in the trunnion 75 16, carrying with it the finer particles of material. Any particles of material too heavy to be carried out by the stream of air or water will be caught within the recess 27 at the discharge end of the device and returned through the centers of the disks for 80 further grinding.

In Figs. 3 and 4 I have shown a modified form of grinding disk. In this form, the disk is shown as comprising an outer section 28 provided upon its inner periphery with a continuous tongue 29 engaging within corresponding grooves formed in the outer periphery of an inner ring 30 formed of arcuate sections, 31, held together at their 90 meeting ends by preferably hard wood wedges 32 seating within corresponding recesses 33 in the ends of the sections. In this form of disk when the outer section becomes worn after long use, it may be removed and 95 replaced by a new section, the sections of the inner ring being interchangeable and being suitable for continuous use. In this form of disk the inner ring sections are provided with registering radially extending grooves 100 34 of the same configuration and arrangement as the grooves in the previously described form of disk. The operation of the device when equipped with this form of disk is identically the same as the operation when 105 the previously described form is employed.

Referring to Figs. 5 and 6 it will be seen that I have provided a still further modified form of disk. In this form, each disk 110 35 is provided with a relatively small central opening 36 and is further provided with a plurality of concentrically arranged series of perforations 37 and 38, the outer series 38 having communicating therewith radially extending grooves 39 which extend 115 to the outer periphery of the disks and which are V-shaped in cross section. This form of disk is particularly adapted for use in "sliming"; that is, when it is desired to grind the material to an extremely fine degree.

It will be noted that in this form of disk the series of perforations 38 and 37 are countersunk so as to be the equivalent of the V-shaped grooves in the other forms of 125 disks while permitting passage of material entirely through the disks. In "sliming", the forms of disks shown in Figs. 1 and 2

and 3 and 4 are removed from the casing and an entire set of the disks shown in Figs. 5 and 6 substituted in place thereof. The operation is the same regardless of which 5 form of disk is used.

From the foregoing description and a study of the drawings it will be apparent that I have thus provided an ore crushing and grinding machine in which all the disk 10 members not only exert a crushing and pounding action at their peripheries on the material introduced into the device, but also rotate relatively to one another, owing to the taper of the casing, whereby the material 15 will be constantly subjected to a grinding action between all the successive disks.

While I have shown and described the preferred embodiment of the invention, it will of course be readily understood that I 20 serve the right to make such changes in the form, construction and arrangement of parts as will not depart from the spirit of the invention or the scope of the appended claims.

Having thus described my invention, what 25 I claim is:

1. A device of the character described comprising a rotary casing, and a plurality of disks of progressively decreasing thickness toward the discharge end and of different diameters disposed within said casing, 30 said disks being adapted to rotate relatively to one another when said casing is rotated, each of said disks being provided with a central opening forming a continuous passageway through said disks and having their 35 confronting faces provided with radially extending grooves extending from the central opening to the outer periphery.

2. In a device of the character described comprising a rotary casing, a plurality of 40 grinding disks each formed of a continuous outer section and an inner section formed of segments and having tongue and groove connection with the outer section, and wedge members engaged between the ends of the 45 segments whereby to hold the inner section expanded, said sections being provided with registering radial grooves.

In testimony whereof I affix my signature.
GEORGE W. MORTHLAND.
